UNITED STATES PATENT OFFICE.

HARRY C. GOODRICH, OF CHICAGO, ILLINOIS.

IMPROVEMENT IN RUFFLING ATTACHMENTS FOR SEWING-MACHINES.

Specification forming part of Letters Patent No. 134,744, dated January 14, 1873.

To all whom it may concern:

Be it known that I, HARRY C. GOODRICH, of Chicago, Illinois, have invented certain new and useful Improvements in Ruffling Attachments for Sewing-Machines; and I do declare that the following is a full, clear, and exact description thereof, reference being had to the accompanying drawing making a part of this specification, in which—

Figure 1 is a plan of my device attached to a Wheeler & Wilson sewing-machine; Fig. 2, a plan of the device alone; Fig. 3, a section on line $\alpha\gamma$ of Fig. 2, looking to the left. Figs. 2 and 3 are full size.

In the drawing, A represents the needle-arm, and E the cloth-plate, of a sewing-machine. a is a pin or stud always found on the needle-arm of the Wheeler & Wilson machine. B is a metal plate, part of my device, with which the other parts are connected. b b' is a bent lever, pivoted to B at e. At the end of the arm b of this lever is a long broad slot, d. To the other arm b' is pivoted the bar C. The other end of this bar C, through which motion is given to my device, is, in use, connected with the pin a and secured thereto in any suitable manner. e e' is a bent bar, to one end of which is secured the thin notched plate f. To the other end is pivoted the piece g. e e' is not directly secured to the plate B; but a portion of the inner edge of B is bent up, forming a shoulder, k, between which and a pin or projection, l, on the plate B, the part e' slides. The part e e' is enlarged at the angle so as to extend under the slot d; and in this enlarged part the pin i rests, which pin i is secured to the upper end of g. By moving the part g to the right or left and changing the position of the pin i in the slot d the length of stroke of f can be adjusted. The device is connected to the cloth-plate E by a set-screw, m, passing through a hole, n, in B. r is an open slot or notch engaging with a projection on E to aid in holding the device in place; as shown, one

of the screws now found on the machine is used at r.

In use the device is operated by the movement of the needle-arm, and in Figs. 1 and 2 the parts are represented in the position which they occupy when the needle is down. In consequence of the wide slot d as the needle rises, C and the lever b b' will move slowly without moving the other parts; but the parts are so adjusted that as soon as the needle is out of the cloth the end b of this lever will come in contact with the pin i, moving e e' and f forward toward the needle; and the points at the end of f being turned up a little, the upper piece of cloth will be carried forward more rapidly than the under piece. As the needle then passes down e e' and f will not move at first, so that the fulled cloth will be held in place until the needle passes into the cloth; then the end of the lever b will come in contact with the pin i, and e e' and f will be carried back to the position shown in the drawing.

D is a cloth-smoother, which, for convenience, I pivot to B.

The cloth upon which the ruffling is to be sewed passes under f, the other piece over f, as usual.

The hole in the bed-plate of my device which receives the thumb-screw by which the attachment is secured to the machine, may be slightly elongated, for the purpose of allowing the device to be adjusted on different machines in the market.

What I claim as new is as follows:

The combination of the plate B, lever b b', bar C, sliding piece e e' f, and the piece g, pivoted to the piece e' and provided with the pin i, substantially as shown and described.

H. C. GOODRICH.
